UNITED STATES PATENT OFFICE

JOSEPH A. PERRY, OF SWARTHMORE, PENNSYLVANIA, ASSIGNOR TO THE UNITED GAS IMPROVEMENT COMPANY, OF PHILADELPHIA, PENNSYLVANIA, A CORPORATION OF PENNSYLVANIA

CARBURETED WATER GAS APPARATUS FOR THE USE OF HEAVY OIL

Application filed November 20, 1929. Serial No. 408,453.

The present invention relates to carbureted water gas.

The object of the invention is to provide improvements in the manufacture of carbureted water gas when utilizing carbureting oils which produce relatively large quantities of coke on vaporization. These oils will be hereinafter referred to as "high coke oils." Such oils, if vaporized, according to the usual carbureted water gas practice, in a checker filled carbureter, deposit sufficient carbon to clog the checker brick in a short time. The frequent cleaning necessary is expensive and reduces, if not cancels, the economy that might be attained by the use of these relatively cheap oils.

It has been proposed to spray such oils on the top of the water gas generator fuel bed during the water gas run and vaporize them there by the heat stored in the top of the fuel bed and the sensible heat of the water gas. However, the water gas operating cycles are of short duration and it is difficult to vaporize sufficient oil on the top of the fuel bed during the run to carburet the gas to the required calorific power for town distribution.

To increase the quantity of oil so vaporized, it has been proposed to heat an annular ring of fuel at the outer margin of the fuel bed top by introducing secondary air at that location during the usual air blasting operation, and to spray the high coke oil onto this heated ring during the steam run. This method is efficacious in increasing the quantity of oil vaporized during the run, but it has an unfavorable effect upon generator fuel economy.

According to the present invention, I spray the high coke oil onto the top of the fuel bed, and increase the heating of the top of the fuel bed during the air blasting operation and also during the steam run by providing a refractory pier, extending upward within the fuel bed to its top or to within close proximity to its top.

During the air blasting operation, the pier stores heat, which it continues to radiate to the fuel bed during the water gas run, a portion of this heat is radiated directly to

the fuel in the top of the fuel bed and is available during the steam run for the increased vaporization of the oil. The pier also heats the uprun water gas rising through the fuel bed near it, which increased sensible heat is available for oil vaporization.

The pier also serves to heat the top of the fuel bed to a greater degree during the air blasting operation, as it secures a more uniform distribution of the resultant hot air blast gases through the top of the fuel bed, and brings them in contact with more fuel. This increased extent of contact is of importance as the time of contact with the fuel is short. The increased contact results in an increased storage of heat in the top of the fuel bed, during the air blast, which is available for increased oil vaporization during the steam run.

If the pier is arranged to project above the top of the fuel bed, radiant heat from the pier aids in vaporizing the finely divided oil, falling through the space above the fuel bed. In such case, I prefer to spray the oil substantially clear of the pier, to prevent the rapid growth of a carbon accumulation on it.

The invention will be more particularly described in connection with the attached drawing, which shows a partial elevation and partial vertical cross section of a carbureted water gas apparatus.

Referring to the drawing,

1 is a water gas generator, 2 a carbureter, 3 a superheater and 4 a wash box.

The generator 1 is provided with the ignited fuel bed 5 containing coal or coke, and with the refractory pier 6 arranged therein and extending upwardly through it from the grate 7. The generator is further provided with the air blast supply means 8 and the steam supply means 9 for upwardly air blasting and steaming the fuel bed. The generator may be provided with the steam supply means 10 for down steaming the fuel bed, but I prefer to introduce the down steam to the superheater as at 11. The generator is provided with the supply means 12 arranged for spraying the high coke onto

the fuel bed. This preferably includes a high pressure nebulizing spray arranged to distribute the oil on the top of the fuel substantially clear of the pier and the side walls 5 of the generator.

The generator is further provided with the offtake 13 for down run water gas, which in the apparatus illustrated leads through the valve 14 to the wash box 4. The connection 15 leads from the generator to the carbureter and serves for the passage of the air blast gases and uprun water gas. 16 is a supply of secondary air to the carbureter. The carbureter 2 is provided with checker 15 brick, diagrammatically indicated at 17, and is connected with the superheater by connection 18. The superheater is provided with the checker brick 19 and with the stack valve 20. The superheater is further provided with the gas offtake 21 provided with valve 22 and leading to the wash box 4. 23 is the gas offtake from the wash box to a place of storage or other disposal, not shown.

A method of operation will now be described. The ignited fuel bed is blasted with air supplied through 8, and the resultant blast gases burned in the carbureter and superheater with air supplied through 16. The burned gases pass to atmosphere through the stack valve 20. When sufficient heat has been stored in the fuel bed, including its top, and in the carbureter and superheater, the air blast is terminated. Valve 20 is closed and with valve 22 open and valve 25 14 closed, an uprun is made with steam supplied to the base of the fuel bed through 9.

At the same time, high carbon oil is sprayed onto the top of the fuel bed through 40 supply means 12. The oil is vaporized by the heat stored in the top of the fuel bed during the air blast, the radiant heat from the pier and walls of the generator and the sensible heat in the uprun water gas passing 45 through the top of the fuel bed. The residues from the oil remain in the fuel bed, and the oil vapors pass with the water gas through the carbureter and superheater, where they are fixed and thence through the 50 wash box where tar is condensed, and to a place of storage.

I prefer to follow the uprun by a steam down run, made by introducing steam to the superheater at 11, superheating it by 55 passing it through the superheater and carbureter and passing it thence downward through the fuel bed in the generator. The superheated steam returns heat to the top of the fuel bed from the superheater and carbureter and aids in drying out and completing the coking of the oil residues on the top of the fuel bed. The resultant vapors pass with the steam through the fuel bed and are cracked there on to gas which 60 65 passes out of the generator through connec-

tion 13 with the water gas resulting from the reaction of the steam and the fuel. The carbon released by the cracking of the oil vapors in part reacts with the down run steam and in part remains in the fuel bed 70 for later utilization. The coke resulting from the oil vaporization on the top of the fuel bed descends with the fuel for subsequent utilization in the lower levels of the fuel bed. During the steam down run above 75 described, valves 20 and 22 are closed and valve 14 is open.

At the conclusion of the steam down run, the above cycle may be repeated.

In the attached drawing, I have shown 80 a single generator, single carbureter and single superheater, as such construction is present standard water gas practice. I may, however, desire to employ two generators in parallel, connected to a carbureter and 85 superheater which are connected in series or to use such generators in other combinations.

The method of operation above described is capable of variations which will readily 90 occur to those skilled in the art.

I claim:

A three shell set for the manufacture of carbureted water gas which includes a water gas generator adapted to contain an 95 ignited fuel bed, a refractory pier within the fuel bed spaced from the outer boundary thereof and extending to a point adjacent the top of the fuel bed and adapted to store heat when the fuel bed is air blasted, means for air blasting the fuel bed, means for passing steam into the fuel bed and passing the resulting water gas through the fuel bed, means adjacent said pier for spraying high coke oil onto the top of the fuel 100 bed, a carbureter containing refractory material and forming a separate vessel from said generator, a superheater containing refractory material and forming a separate vessel from said generator and from said 105 carbureter, gas conduit connections between said generator and said carbureter and said superheater, and means for leading off gas from the top of said superheater and from the bottom of said generator.
